(57) **CLAIM**

The ornamental design for a golf club head, as shown.

DESCRIPTION

FIG. 1 is a rear perspective view of a golf club head.

FIG. 2 is a side view of the toe end of the golf club head of FIG. 1.

FIG. 3 is a side view of the heel end of the golf club head of FIG. 1.

FIG. 4 is a front elevation view of the golf club head of FIG. 1.

FIG. 5 is a top view of the golf club head of FIG. 1.

FIG. 6 is a rear elevation view of the golf club head of FIG. 1; and,

FIG. 7 is a bottom view of the golf club head of FIG. 1. The broken lines in the figures form no part of the claimed design.
